UNITED STATES PATENT OFFICE.

EMIL J. HANSEN, OF GREEN BAY, WISCONSIN, ASSIGNOR TO FORT HOWARD PAPER COMPANY, OF GREEN BAY, WISCONSIN, A CORPORATION OF WISCONSIN.

FOLDED SHEETS OF MATERIAL.

Application filed September 12, 1924. Serial No. 737,281.

The invention relates to improvements in a folded tissue or thin paper sheets for use as napkins, towels, toilet paper or the like, and to a stack or pile of peculiarly folded 5 individual thin paper sheets having predetermined size in accordance with the holder therefor.

The primary object of the invention is the provision of a stack or pile of paper sheets, 10 in which the several superposed sheets are arranged independently and separate from each other, but which engage one with the other during the removing or discharging operation, so that the lowermost sheet of the 15 stack or pile is always accessible and can be readily grasped for the removal thereof from the holder, without liability of the tearing of the sheet or the next sheet adjacent thereto.

20 With these and other objects in view the invention consists in the features of construction, combination and arrangement of parts, as will be hereinafter fully described, illustrated in the accompanying drawings 25 and pointed out in the claims hereunto appended.

In the accompanying drawings:

Figure 1, is a perspective view of a serving cabinet in which the folded sheets of material constructed in accordance with the invention are contained.

Figure 2, is a vertical sectional view thereof.

Figure 3, is a perspective view of one of the 30 individualized folded sheets of material.

Figure 4, is a view similar to Figure 3, of another individualized folded sheets of material.

Similar reference characters indicate corresponding parts throughout the several 40 views in the drawings.

Referring to the drawings in detail, A, designates generally a suitable cabinet for containing the stack or pile of paper sheets 45 from which the same may be delivered singly and successively, and wherein the removal of one sheet causes the next succeeding sheet to be moved to position for its extraction from the cabinet, as said sheet may be readily taken 50 hold of and withdrawn.

The cabinet A, comprises a body 10, preferably made from sheet metal, although the same may be constructed from any other suitable material, and has formed in one wall 55 thereof medially of the same a slot 11, which

is disposed longitudinally of said wall and at each end intersects a semi-circular shaped notch 12, formed in the end wall 13, the edges of the slot 11, next to the notch 12, being rounded at 14, so as to prevent any possibility of the paper sheets becoming torn when being extracted from the cabinet on withdrawing said sheets, as will be hereinafter fully described.

The cabinet A, is provided with a removable section 15, so that the same can be conveniently filled with the paper sheets as the occasion may require. It is to be understood that changes and variations may be made in the cabinet as come properly within the scope of the claims hereunto appended, 70 without departing from the spirit of the invention or sacrificing any of its advantages.

In the cabinet A, is adapted to be stacked or piled a series of superimposed paper sheets 75 C, or D, each being hereinafter more fully described.

The paper sheet C, shown in Figure 3, of the drawings, is first folded on a median line; thence again folded along a median line at 80 right angles to the first named fold, and finally folded at each end along parallel lines to form tabs 20, these being folded on the same side of the body of the sheet. The tabs 20, are exposed at the slot 11, in the cabinet 85 A, when the sheets are stacked or piled therein in superimposed relation to each other.

The sheet D, shown in Figure 4, of the drawings, is folded along a median line, then again folded at each end along parallel lines, 90 and finally folded transversely along a median line as at 21, relative to the parallel folds, to provide tabs 22, which lie on the same side of the body, so that this folded sheet can be reversed and the tabs 22, at all 95 times will be exposed, as will be apparent.

It will be obvious that when the sheets C, or D, are stacked or piled in the body of the cabinet A, they will not interlock with each other, and can be individually withdrawn 100 through the slot 11, from within the cabinet A, without liability of the tearing on the next succeeding sheet.

Within the body of the cabinet A, is a follower plate 23, against which acts a coiled 105 expansion spring 24, the latter being connected to the removable section 25, of the said cabinet, and to the follower plate 23, and in this manner the stack or pile of sheets are kept compact and advanced within said cabinet, 110

the follower being disposed against the uppermost sheet of the stack or pile placed in said cabinet as will be clearly apparent.

What is claimed is:

- 5 1. An element for use in a dispensing package, wherein the folded sheets are superimposed one upon the other, comprising the following structure, namely a sheet of paper comprising a body folded to form a plurality of tabs at the same side of the sheet and overlapping the body of said sheet, said tabs being in contact with the same side surface of the sheet, the body and tabs being further folded on a transverse line, whereby the body will be surrounded by the tabs and the latter

will be exposed at opposite sides of said folded body.

2. An element for use in a dispensing package, wherein the folded sheets are superimposed one upon the other, comprising the following structure, namely, a body folded to form a plurality of tabs at the same side of the sheet and overlapping the body of said sheet, said tabs being in contact with the same side surface of the sheet, the body and tabs being further folded on a transverse line whereby the body will have two sets of exposed tabs on opposite sides thereof. 20

In testimony hereof I affix my signature.

EMIL J. HANSEN. 25
